UNITED STATES PATENT OFFICE.

EDWIN M. JENKINS AND ROBERT E. JACKSON, OF PRINCETON, WEST VIRGINIA.

FLUE-CLEANING APPARATUS.

1,416,209.

Specification of Letters Patent. Patented May 16, 1922.

Application filed March 24, 1919. Serial No. 284,771.

To all whom it may concern:

Be it known that we, EDWIN M. JENKINS and ROBERT E. JACKSON, citizens of the United States, residing at Princeton, in the county of Mercer and State of West Virginia, have invented certain new and useful Improvements in Flue-Cleaning Apparatus, of which the following is a specification.

The present invention relates to improvements in apparatus for cleaning the flues or tubes of railway locomotive boilers or other boilers.

An important object of the invention is to provide apparatus of the above-mentioned character which is adapted to be operated from the exterior of the boiler so that it is not necessary to wait until the boiler cools.

A further object of the invention is to provide apparatus of the above-mentioned character which is simple in construction, inexpensive to manufacture, and reliable in operation.

Other objects and advantages of the invention will be apparent during the course of the following description.

In the accompanying drawings forming a part of this specification and in which like numerals are employed to designate like parts throughout the same:

30 Figure 1 is a central vertical longitudinal sectional view through the fire-box of a railway locomotive, showing a portion of my apparatus arranged therein, in a position for cleaning one of the flues or tubes;

35 Figure 2 is an end elevation of the apparatus, in use, the fire-box being shown in section on line 2—2 of Figure 1;

40 Figure 3 is a central longitudinal sectional view through the cylinder and associated elements of the cleaning apparatus;

Figure 4 is a side elevation of the supporting element of the apparatus;

Figure 5 is a transverse sectional view, taken on line 5—5 of Figure 4;

45 Figure 6 is a similar view, taken on line 6—6 of Figure 3;

Figure 7 is a perspective view of the cylinder and associated elements, showing the inner slotted side of the tubular support;

50 Figure 8 is a side elevation of a cover or plate;

Figure 9 is a transverse sectional view through the cover and associated elements; and

55 Figure 10 is a detail section of a slightly

different form of nozzle receiving contact member.

In the drawings, wherein for the purpose of illustration is shown a preferred embodiment of our invention, the numeral 20 designates the fire-box of a railway locomotive, having at its rear end an opening 21, for the introduction of the coal. At the forward end of the fire-box are the tubes or flues 22, to be cleaned. The sides of the fire-box are provided with openings, in transverse alinement, and receiving thimbles 23', which are adapted to loosely receive a transverse tubular support 24. The outer ends of the thimbles are surrounded by a reinforcing ring 25, rigidly held in place by bolts 26. This reinforcing ring is adapted to be covered by a door or head 27, held in place by a lever 28, pivoted thereto, as shown at 29. The ends of the lever are adapted to engage within latches 30, having oppositely extending openings, and rigidly secured to the ring 25. When the flue cleaning apparatus is not being employed, the thimbles are closed by the doors or covers 27, as is obvious, these doors being readily removable.

The tubular support 24 is provided upon its forward side with a longitudinal opening or slot 31, for a purpose to be described, and brackets 32 are rigidly secured to the rear side of the tubular support, the outer brackets having connection with brace rods 33, engaging within recesses formed in the inner brackets 32. The inner ends of the rods 33 have screw threads, oppositely pitched for engagement with a turn-buckle 34, as shown. It is thus seen that means are provided to reinforce the tubular support. The tubular support has a crank or handle 35 secured to one end thereof, to turn the same, or hold the same against turning movement.

The numeral 36 designates an air supply pipe, one end of which projects outwardly beyond one end of the tubular support 24, as shown in Figure 2. This supply pipe 36 is provided exteriorly of the tubular support 24 with a valve 36'. The pipe 36 is detachably connected with a hose or the like having suitable connection with a source of compressed air or other fluid pressure. As more clearly shown in Figure 6, the opposite end of the air supply pipe 36 is screw threaded for engagement within an opening 37 of a coupling 38, which is flattened to operate within the longitudinal opening 31. 110

This coupling also serves to prevent the pipe 36 from turning upon its longitudinal axis with relation to the tubular support 24.

The coupling 38 has its forward end 5 screw-threaded, for connection with a head 39, screw-threaded to a cylinder 40. The opposite end of this cylinder is closed by a head 41 having screw threaded engagement therewith. The head 41 has screw threaded 10 engagement with a tube 42, carrying a cap 43, screw-threaded therewith. Mounted to reciprocate within the cylinder 40 is a piston 44, having connection with a tubular piston rod 45, extending through the cap 43. The 15 piston 44 is provided with an opening 46, in communication with the bore of the tubular piston rod 45, and a compressible coil spring 47 surrounds the tubular piston rod 45 and serves to return the piston 44 to the normal 20 starting position when the supply of fluid pressure is cut off from the cylinder 40, the piston being moved forwardly when the fluid pressure is introduced therein.

Connected with the forward end of the 25 tubular piston rod 45 is a preferably globular nozzle 48, provided with a forward outlet opening 49. This nozzle is mounted to turn in an opening formed in a two-part contact ring or member. This member comprises 30 a forward part 51, a rear part 52, and bolts 50 serving to connect the same. The nozzle 48 is free to turn in the contact ring, and the contact ring may be angularly adjusted upon the globular nozzle 48.

In Figure 10, we have shown a different 35 form of contact ring, the same being preferably formed in two sections 54 and 55, which may be of wood, secured together by screws 56. This contacting ring is also angularly adjustable upon the nozzle 48.

The operation of the apparatus is as follows:

The tubular coupling 38 is disconnected 45 from the pipe 36 and the cylinder 40 and coupling 38 and associated elements introduced into the fire-box of the locomotive by passing the same through one of the thimbles 23 which has a suitably large diameter, for this purpose. The cylinder and associated elements are now suitably supported or held in the fire-box by tongs or like implements passed through the thimble and the air supply pipe 36 is next screwed into the opening 37. This pipe now serves as a 50 temporary support for the cylinder 40 and associated elements. The tubular support 24 is now passed through the two thimbles 23, the coupling 38 passing through the longitudinal opening 31 in the tubular support.

The cylinder 40 and associated elements are longitudinally adjusted by sliding the compressed air supply tube within the tubular support, so that the nozzle 48 is brought into alinement with a vertical row of tubes or 55 flues. The tubular support 24 is turned

upon its longitudinal axis by means of the crank 35 to angularly adjust the cylinder 40 and associated elements, so that the nozzle head 48 may be brought in alinement with the selected tube or flue in the vertical 70 row. The compressed air is now supplied to the tube 36 by opening the valve 38', and this compressed air forces the piston 44 forwardly, causing the contact plate to enter the rear end of the flue. The compressed 75 air also passes in the flue to clean the same. As soon as the supply of compressed air is cut off, the spring 47 will automatically return the piston 44 to the rear position, withdrawing the contact plate 50 from within the rear end of the flue, thereby allowing of the turning movement of the tubular support 24, to bring the contact ring in alinement with another flue in the same vertical set.

It is to be understood that the form of our invention herewith shown and described is to be taken as the preferred example of the same, and that various changes in the shape, size, and arrangement of parts may 90 be resorted to without departing from the spirit of our invention or the scope of the subjoined claims.

Having thus described our invention, we claim:—

1. In apparatus of the character described, the combination with a boiler having flues and a fire box, said fire box having openings formed in its sides, of a rotatable support extending through said openings and arranged in the fire box, and a longitudinally extensible flue cleaning device adapted to be passed through one of said openings, said cleaning device being movable longitudinally of said support.

2. In apparatus of the character described, the combination with a boiler having flues and a fire-box, said fire-box having openings formed in its opposite sides, of a flue cleaning device adapted to be passed through one of the openings, a supporting element adapted to be passed through the fire box with its end portions projecting into the openings, means for detachably connecting the cleaning device with the supporting element, said cleaning device being adjustable longitudinally to contact with the end of the flue, and means whereby the supporting element may be turned upon its longitudinal axis.

3. In apparatus of the character described, the combination with a boiler having flues and a fire-box, said fire-box having openings formed in its opposite sides, of a longitudinally extensible fluid pressure operated flue cleaning device adapted to be passed through one of the openings, a transverse supporting element arranged within said openings, means connecting the flue cleaning device with the supporting element

so that the device may be adjusted longitudinally of the supporting element, means for supplying fluid pressure to the device, and means whereby the supporting element may be turned upon its longitudinal axis.

4. In apparatus for cleaning the flues of a boiler having a fire-box provided in its sides with openings, a tubular support arranged within the openings and provided 10 upon its forward side with a longitudinal slot, fluid pressure operated flue cleaning apparatus adapted to be passed through one of the openings, a fluid pressure supply pipe longitudinally adjustably mounted within 15 the tubular support, a coupling connected with the fluid pressure supply pipe and extending through the longitudinal slot and connected with the flue cleaning apparatus, and means whereby the tubular support may 20 be turned upon its longitudinal axis.

5. In apparatus of the character described, a tubular support provided upon one side with a longitudinal slot, a pipe 25 slidably mounted within the tubular support, a coupling operating within the longitudinal slot and connected with the pipe, a cylinder connected with the coupling, a piston mounted to reciprocate within the cylinder and having an opening formed therein, 30 a tubular piston rod connected with the piston and having its bore in communication with the opening of the piston, a spring to move the piston in one direction, and a nozzle connected with the forward end of the 35 tubular piston rod.

6. In apparatus of the character described, a tubular support provided upon one side with a longitudinal slot, a pipe extending into the tubular support, a coupling 40 operating within the longitudinal slot and connected with the pipe, a cylinder connected with the coupling, a piston mounted to reciprocate within the cylinder and having an opening formed therein, a tubular 45 piston rod connected with the piston and having its bore in communication with the opening of the piston, a spring to move the piston in one direction, a nozzle connected with the tubular piston, and a contact ring 50 pivotally receiving the nozzle.

7. In apparatus of the character described, a tubular support provided upon one side with a longitudinal slot, a coupling 55 slidably mounted within the slot and provided within the tubular support with a screw threaded opening, a pipe having one end screw-threaded to engage within the

screw threaded opening, a fluid pressure operated flue cleaning device carried by the coupling, and means whereby the tubular support may be turned upon its longitudinal axis.

8. In apparatus of the character described, a tubular support provided upon one side with a longitudinal slot, reinforcing means arranged upon the opposite side of the tubular support and extending longitudinally thereof and connected therewith, a coupling slidably mounted within the tubular support and having a portion thereof extending through the longitudinal slot, means to supply fluid pressure to the coupling, a fluid pressure operated flue cleaning device carried by the coupling, and means whereby the tubular support may be turned upon its longitudinal axis.

9. In apparatus of the character described, a supporting element adapted to be arranged transversely of the boiler, a fluid pressure operated flue cleaning device carried thereby and adjustable thereon, means whereby said cleaning device may be aligned with the end of a flue, and means operable by the admission of fluid pressure thereto to longitudinally extend said cleaning device.

10. In apparatus of the character described, a supporting member adapted to be arranged transversely of the boiler, a fluid pressure operated flue cleaning device carried thereby and adjustable thereon, said flue cleaning device being provided with a flue engaging end, and means operable by the admission of fluid pressure thereto to longitudinally extend said cleaning device 95 to bring the flue engaging end thereof into engagement with a flue of the boiler.

11. In apparatus of the character described, a supporting member adapted to be arranged transversely of the boiler, a flue 100 cleaning device carried thereby and adjustable thereon, said flue cleaning device being provided with a flue engaging end, means for adjusting said flue cleaning device on said support, and pressure operated means 105 for extending said flue cleaning device upon its longitudinal axis.

In testimony whereof we affix our signatures in presence of two witnesses.
